UNITED STATES PATENT OFFICE.

HOWARD G. WIDMER, OF BROOKLYN, NEW YORK, ASSIGNOR TO ARKELL SAFETY BAG COMPANY, OF NEW YORK, N. Y., A CORPORATION OF NEW YORK.

MACHINE FOR OPERATING ON PAPER.

1,362,976.

Specification of Letters Patent. Patented Dec. 21, 1920.

Application filed May 11, 1917. Serial No. 167,855.

To all whom it may concern:

Be it known that I, HOWARD G. WIDMER, a citizen of the United States, and a resident of the borough of Brooklyn, county of 5 Kings, and State of New York, have invented certain new and useful Improvements in Machines for Operating on Paper, and More Particularly for Forming Tubes from Sheets of Paper Fed Thereto, of which 10 the following is a specification, reference being had to the accompanying drawings, which form a part hereof.

The invention, considered as a whole, seeks particularly to provide a machine 15 whereby sheets of paper may be cut off from a continuous web of crinkled paper fed thereto, then folded transverse to the web so as to bring together the ends of the sheet and then securely seam together the meeting 20 edges of the paper, the machine operating automatically and continuously to carry out its operation of feeding, cutting, folding, seaming and delivering in an economical manner.

25 The invention consists of the various features and their arrangement and combination hereinafter pointed out.

In the accompanying drawings forming part of this specification, and in which like 30 reference numerals designate corresponding parts, the invention and its various features are shown in the preferred form and are embodied in a complete operative machine.

In the drawings,

35 Fig. 1 is a side elevation of the machine. Fig. 2 is a sectional elevation of the principal parts of the machine taken on the line 2—2 of Fig. 3.

40 Fig. 3 is a front elevation looking in the direction of the arrows 3 of Fig. 1 and showing the feed and cutting rolls, parts being broken away.

Fig. 4 is an elevation looking in the direction of the arrow 4 and showing the 45 seaming and pasting rolls, parts being broken away.

Fig. 5 is an end elevation of portions of the feed and cutting rolls showing the cutting mechanism associated therewith.

50 Fig. 6 is a plan view of the upper roll shown in Fig. 5 looking from beneath.

Fig. 7 is a plan view of the lower roll shown in Fig. 5 and showing the cutting knife carried by said roll.

55 Fig. 8 is a sectional elevation taken on the line 8—8 of Fig. 7.

Fig. 9 is a sectional elevation taken on the line 9—9 of Fig. 8.

Fig. 10 is an end elevation showing parts of the upper feed roll and of the associated 60 seaming and pasting roll.

Fig. 11 is a plan view of the structure shown in Fig. 10 looking in the direction of the arrow 10.

Fig. 12 is an end elevation showing parts 65 of the seaming and pasting rolls.

Fig. 13 is a plan view of a portion of the lower seaming and pasting roll shown in Fig. 12, taken in the direction of the arrow 13 of Fig. 12, parts being omitted.

70 Fig. 14 is an end elevation of the same seaming and pasting roll showing the seaming elements carried by this roll in their normal position.

Fig. 15 is a plan view showing one end 75 of the roll shown in Fig. 14.

Fig. 16 is a view similar to Fig. 14 but showing the seaming elements in different position.

Fig. 17 is a section of a detail on line 80 17—17 of Fig. 18.

Fig. 18 is a plan view of Fig. 17.

Figs. 19 and 20 are details, the former taken on line 19—19 of Fig. 1 when the receiving pan has been retracted.

85

Referring now to the particular structure shown in the drawings, 1 is the main frame of the machine on which are mounted the various moving elements. The driving shaft 2 carrying the driving pulley 3 carries a 90 gear 4 which meshes with the gear 5 fixed on one end of the shaft 6. Gear 5 meshes with and drives gear 7 fixed on the shaft 8, on which shaft is fixed the seaming and pasting roll 9. Gear 7 meshes with and 95 drives gear 10 fixed on the shaft 11, on which shaft is fixed the creasing and paste applying roll 12.

Shaft 6 also carries on its end opposite from gear 5 a gear 16 which meshes with 100 and drives gear 17 fixed on the shaft 18 on which shaft is mounted the feed and cutting roll 19. Gear 17 meshes with and drives a gear 20 fixed on shaft 21 which shaft carries the feed and cutting roll 22 coöperating 105 with roll 19.

The web of crinkled paper 23 passes over a roll 24 driven by a belt 25 from a pulley 13 on shaft 121. The web then passes over two fixed rods 26 and 27 and between the rolls 110 19 and 22. The rod 26 is carried by and between two guide disks 28 fixed on the ends

of a rod 29 supported by posts 30. The rod 27 is similarly mounted and arranged. The roll 24 is driven just fast enough to produce a certain amount of slack in the web just before it passes over rod 26, as indicated in Fig. 1, thereby facilitating an easy and uniform feed of the web to the machine. Surrounding the shaft 21 at its ends are two sleeves 31 and 32 which are fixed against rotation in the boxes 33 and 34 supporting the shaft. On these sleeves 31 and 32 are two stationary cams 35 and 36. 37 is a rock shaft mounted in the roll 22 and carrying a series of arms 38 provided with pins 39 at their outer ends, see Figs. 3, 5 and 6. The ends of the rock shaft 37 are provided with fixed arms 40 and 41 having rollers at their outer ends riding on the cams 35 and 36. A spring 42, having one end secured to a lug 20 on the rock-shaft and the other end to the roll 22, serves to keep the arms 40 and 41 in contact with their cams 35 and 36. Fixed radially in the periphery of the roll 22 is a knife 43 having a serrated cutting edge. 25 Also fixed radially in the periphery of the roll 22 is a bar 44 separated a short distance from the knife 43 so as to provide a channel between it and the knife 43. Moving radially in a slot formed in the periphery of 30 the roll 19 is a knife 45 having a serrated beveled edge, see Figs. 7, 8 and 9. This knife is riveted at its ends to blocks 46 and 47. These blocks, together with the knife 45, are arranged to reciprocate between pairs of 35 guide brackets 48 and 49 fixed on the opposite ends of the roll 19. Radial movement is imparted to the knife by cams 50 and 51 which engage the rollers 52 and 53 fixed on the blocks 46 and 47, respectively. Springs 40 54 and 55 keep these rolls in contact with their cams. These springs are connected at one end to the blocks and at their other ends to sleeves 56 and 57 fixed in the boxes supporting the shaft 18 of roll 19, see Fig. 3. 45 Cams 50 and 51 are fixed on these stationary sleeves. Riveted to the lower margin of the knife 45 is a bar 58 through which loosely pass parallel with the knife a series of bolts 59 surrounded by springs 60 and at their upper ends screwed into a bar 61 lying close against the knife and whose upper surface projects slightly above the surface of the roll 19. The springs 60 fit in recesses in the bars 58 and 61. These bars and the knife 55 are located in a radial recess 62 formed in the periphery of the roll 19. On the side of the knife 45 opposite to the bars 58 and 61 is another bar 63 which is fixed in the recess 62 in roll 19 and forms a guide for the knife 60 45 in its reciprocating movement.

As shown in the drawings, rolls 19 and 22, instead of being formed with a continuous surface, are formed of separated narrow cylindrical sections each fixed securely upon its shaft. This arrangement

saves material and furthermore, in connection with roll 22, enables the arms 38 on rock shaft 37 to be mounted between the sections of that roll. One of the functions of these rolls 19 and 22 is to receive and feed forward the web of paper and, when such paper is crinkled, it is advantageous that one of these rolls be provided with teeth on its periphery. In the present instance, the upper roll is provided with teeth 64. These teeth 70 engage the paper and feed it forward reliably and uniformly to the knives 43 and 45 without unduly stretching the paper. If both rolls were smooth faced the feed of the crinkled paper would necessarily depend 75 upon its continuous frictional engagement by and between such smooth faced rolls and the crinkles would be injured and the paper unduly stretched. One of the rolls, as roll 19, may have a smooth surface, as shown. 80 85

In the operation of the rolls 19 and 22 and their knives, see Figs. 5 and 9, when a predetermined length of the paper web has passed between the rolls and just before the knives 43 and 45 come into alinement, bar 90 61, which projects slightly above the periphery of the roll 19, grips the paper between it and the coöperating bar 44 on roll 22, bar 61, owing to its spring mounting, yielding to the pressure put upon it by the bar 44. At 95 substantially the same time arms 40 and 41 pass beyond the elevated portions of their coöperating cams 35 and 36 and the spring 42 rocks the shaft 37 so as to throw the pins 39 forward and outward through the paper 100 on a line just back of the knife 43. At substantially the same time rollers 52 and 53 of knife 45 pass on to the elevated portions of their cams 50 and 51 thereby moving knife 45 outward so as to sever the paper in coöperation with knife 43. As the rolls 19 and 22 continue their movement the knife rollers 52 and 53 travel off of the elevated portions of their cams and knife 45 is retracted by its springs 54 and 55. At the same time the 105 pins 39 carry the paper which they have engaged around with roll 22 and continue to thus engage the paper until the arms 40 and 41 have traveled slightly beyond three-quarters of a turn when they ride up on the elevated portions of their cams and thereby retract the pins from engagement with the paper. As the rolls continue their movement the knives repeat their action to cut off another length of paper and the pins 39 repeat their action to engage a new length of paper just entering between the rolls. 110 115 120

Fixed on roll 22 and lengthwise therewith is a fold-forming knife 65, see Figs. 10 and 11, located almost diametrically opposite the 125 pins 39 when the latter are in their engaging position. When these pins, in engagement with a strip or section of the paper, have traveled slightly beyond a three-quarter turn, the bar 65 will be in the position of 130

its nearest approach to roll 9 and will be lying beneath the strip engaged by the pins. Just as the pins release the paper, folding grippers 66 carried by the roll 9 seize the 5 paper in a fold at the knife 65 thereby carrying the paper doubled over on itself in a fold from roll 22 on to roll 9. The strip caught by the grippers 66 and being carried over on to roll 9 is not cut off from the 10 web until the roll 22 has traveled slightly beyond another quarter turn. By this arrangement, the lower fold of the strip on roll 9 is slightly longer than the upper fold, as shown in Fig. 14. The grippers 66 are 15 mounted on the rock shaft 67 carried by the roll 9, the grippers projecting between the sections composing the roll. The ends of these grippers normally rest on a bar 68 extending across the roll 9 and projecting 20 slightly beyond its surface. Rock shaft 67 is provided with arms 69 and 70 having cam rollers on their ends which ride on the cams 71 and 72, see Fig. 4. These cams are fixed on stationary sleeves 73 and 74 surrounding the shaft 8 of roll 9, being rigidly held in place by the boxes which carry the shaft 8. A spring 75, see Fig. 10, connected at one end to a lug 76 on the shaft 67 and at the other end to the roll 9 serves to keep the 25 grippers 66 normally down upon their gripper bar 68 and the arms 69 and 70 in engagement with their cams. When the grippers come opposite the fold-forming knife 65 of roll 22, in the position shown in Figs. 30 10 and 11, the arms 69 and 70 pass off of the elevated portions of their cams and the grippers 66 form a crease in the paper in conjunction with knife 65 and bar 68. Knife 65 is provided with recesses 77 to enable the 35 grippers 66 to pass through the knife, carrying with them the fold in the paper and pressing the fold against bar 68. The grippers 66 continue to grip the paper until they have made a half turn from the position shown in 40 Fig. 10 when they are retracted to release the paper due to the action of cams 71 and 72 and spring 75.

The chief function of roll 9, in conjunction with roll 12, is to form the seam and 45 paste together the abutting edges of the folded sheet. For this purpose roll 9 is provided with seaming devices including pasting devices which will now be described, referring particularly to Figs. 12 to 16, inclusive. Across the surface of roll 9 extends a recess 78 in which loosely rests a bar 79 connected at its ends with and carried by side arms 80 and 81. Each of these arms is provided with a slot 82, one slot being associated with sleeve 73 and the other with sleeve 74 surrounding the shaft 8. These arms are provided with cam rollers 83 and 84 which ride on cams 85 and 86 fixed on sleeves 73 and 74. Each of these arms 80 55 and 81 is provided with three springs 87,

88 and 89 which are connected at one end to the arms and at the other end to the roll 9 and act to return these arms and bar 79 to their normal position when they have been moved therefrom. Cams 85 and 86 act 70 to move the arms and the bar 79 radially outward. The ends of the arms 80 and 81 opposite the bar 79 extend beyond the shaft 8 and each is provided with a slot 90 in which works a roller 91. These rollers are 75 carried by clips 92 and 93 mounted on pins 94 and 95 and carry cam rollers 96 and 97 which engage the cams 98 and 99 on the sleeves 73 and 74. Mounted on the periphery of the roll parallel with the bar 79 and 80 immediately forward thereof is a channel bar 100 provided with the crease-forming channel 101.

Coöperating with the channel bar 100 are grippers 102 mounted on the rock shaft 103 85 carried by the roll 9, see Figs. 4, 12 and 13. Fixed to this rock shaft are arms 104 and 105 having cam rollers which engage the cams 106 and 107 fixed on the sleeves 73 and 74. A spring 108 having one end fixed 90 to the roll 9 and the other end fixed to a lug secured to rock shaft 103 acts to hold the cam arms down on their cams and tends to throw the grippers 102 forward against the front wall of the channel 101. The rear 95 side of the channel bar 100 is provided with recesses 109 to permit the grippers 102 to pass through toward the front wall of the channel 101. The roll 9 is provided with a smooth surface and is composed of separate 100 sections like the roll 19.

Coöperating with the roll 9 is the seaming and pasting roll 12 composed of separated sections and having teeth thereon similar to the roll 22. This roll is provided with a 105 paste carrying bar 110 extending across its periphery and with the crease-forming knife 111 immediately forward of the bar 110. It is provided with recesses similar to and registering with recesses 109 in channel bar 100 110 to permit the grippers 102 to pass through to engage the paper before the knife retreats from the channel 101.

In the operation of the seaming and pasting rolls 9 and 12, when the rear edges of 115 the folded strip of paper have come between the rolls 9 and 12, the excess margin of the lower fold of the paper constituting the seam flap 112 is squeezed between the paste carrying bar 110 and the bar 79, thereby 120 applying paste to the upper surface of the seam flap. While this is being done, the crease-forming knife 111 has entered the crease channel 101 carrying both folds of the paper with it to form the seam crease. In 125 the meantime, the cam arms 104 and 105 have passed on to the lower portions of their cams thereby throwing the grippers 102 forward to press the paper against the front wall of channel bar 100. The position 130

of the parts at this stage is shown in Fig. 12. As the rolls continue their movement, knife 111 moves out of the crease lying within the crease channel and the grippers 102 continue to press the crease against the front wall of the crease channel. The crease in the paper at this stage and the position of the bar 79 is shown in Fig. 14. As the rolls continue their movement, arms 80 and 81 are elevated by their cams 85 and 86 thereby causing the bar 79 to lift the seam flap 112. As the roll 9 continues its movement, rolls 96 and 97 of cam clips 92 and 93 ride up on the elevated portions of their cams 98 and 99 thereby throwing the bar 79, now elevated, forward to carry the flap 112 over the outer fold of the paper and also over the narrow seam flap 113 thereof. Immediately thereafter the bar 79, owing to the shape of the cams 85 and 86 and the action of springs 87, 88 and 89, moves inward. These three movements of the bar 79, outward, then forward, then inward, bring the underside of the bar 79 on top of the flap 112 as the same lies upon the outer surface of the upper fold of the paper, and the parts are in the position shown in Fig. 16. The flap 112, having paste on its under surface, is now pressed down by bar 79 upon and pasted to the outer surface of the outer fold of the paper. While the parts are in this position, shown in Fig. 16, the bar 79 is squeezed down firmly to effect a secure pasting of the seam flap by means of a bar 114 carried by four arms 115 mounted on the shaft 116. The shaft 116 is driven by a gear 117 fixed on the shaft and meshing with gear 7 fixed on shaft 8. The folded strip of paper upon which the parts have operated to form the seam is now in the form of a tube indicated by the numeral 118 whose extent is half the circumference of the roll 9. After the operation of the squeezing bar 114 has been completed, bar 79 is restored to its normal position in the recess 78 by means of its cams and springs.

For the purpose of carrying paste to the paste carrying bar 110, a bar 119 is provided. It is mounted on a plurality of arms 120 fixed on shaft 121 on which is mounted the gear 122 meshing with gear 10, see Fig. 1. 123 is a paste box carried by two brackets 124 secured to the main frame. The paste roll 125 rotates in the paste box and is carried on the shaft 126 mounted on the brackets 124 which shaft is driven from the gear 122. The paste bar 119, coming in contact with the paste roll 125, receives its supply of paste which it in turn applies to the paste bar 110. Coöoperating with the roll 9 is a series of flat springs 127 fixed on a rod 128 and bearing down upon the upper surface of the roll to smooth the paper against the roll, see Figs. 2 and 20.

65 Tube 118 is removed from the machine

by the mechanism that will now be described, see Figs. 1 and 2. 129 is a receiving pan having a high back and a sloping bottom. It is located between the rear horizontal extension of the main frame on 70 which it is arranged to slide to and fro. For this purpose angle brackets 130 are secured to the back of the pan on either side and to U-shaped slide bars 131 which extend from the front of the pan to a short 75 distance in the rear thereof. These slide bars are held in place by guide bars 132, see Fig. 19. Bolted to the slide bars 131 are draw bars 133 extending to the rear and provided at their rear ends with rollers 134, 80 see Figs. 17 and 18. These draw bars are provided with slots 135 immediately in front of their rollers 134 through which passes a shaft 136. Fixed to each end of this shaft is a cam 137 and a friction wheel 85 138, the latter being provided with strips of suitable friction material 139 extending about a third way around their peripheries. By this arrangement, as the shaft 136 rotates, the cams, carried with it, contact with the rollers 134 pushing them to the rear and thereby carrying the pan 129 rearward. When the cams have passed out of contact with the rollers 134, springs 140, see Fig. 2, pull the pan forward into the 95 position shown in Fig. 2. This pan has, thus, a reciprocating movement forward and backward. The grippers 66 holding the forward end of the tube 118 are retracted by their cams to release the tube when 100 they have arrived just above the forward end of the pan so that this end is deposited in the receiving pan where its forward edge comes to rest against the back of the pan, and the body of the tube after forming one 105 or two loops overhangs the front of the pan, as shown in Fig. 2. In order that the rear portion of the tube may overhang the pan the pan is caused to move to the rear by the mechanism already described. When 110 about four-fifths of the tube has been deposited in the pan and the grippers 102 holding the rear end of the tube have reached a point well in front of the pan they are retracted by their cams, thereby 115 causing the last portion of the tube that leaves the roll 9 to fall outside the front edge of the pan and overhang it. The pan is then moved forward by its springs 140 to bring the front or seamed edge of the 120 tube between the carrier tapes 141 and 142. These tapes 141 and 142, see Figs. 1 and 2, run over suitable guide pulleys and run in the same direction close together from a point where the tube is deposited between 125 them to and around the roll 143 where they separate, the tapes 142 passing entirely around the roll 143 and thence down and back to the starting point, and the tapes 141 passing over the top of the roll 143 and 130

thence around a roll 144 and back to their starting point. The tapes 142 are driven by the roll 143 on the shaft 163 on which are also fixed a sprocket wheel 145, on the 5 near end of the shaft and a second sprocket wheel (not shown) on the far end of the shaft. The tapes 141 are driven by the roll 143 and also by the roll 144 on the same shaft with which is fixed a sprocket wheel 10 146. The sprocket wheel 146 is driven from sprocket wheel 145 by a sprocket chain 164 which passes around the sprocket wheel on the far end of shaft 163, thence partly around sprocket wheel 146 and thence 15 around an idle sprocket wheel 148. Shaft 163 is driven by a sprocket chain 147 which passes around sprocket wheel 145 and around sprocket wheel 149 on shaft 150. Shaft 150 is driven by the sprocket chain 20 151 which passes around a sprocket wheel on shaft 150 alongside the sprocket wheel 149 and thence around the sprocket wheel 152 fixed on the shaft 116.

On the shaft 136, whose movement actuates the pan 129, is fixed a sprocket wheel 153 which is driven by a sprocket chain 154 which passes around sprocket wheel 153, also part way around a sprocket wheel 155 fixed on the shaft 150, thence over two 25 sprocket pulleys back to sprocket wheel 153.

On the rock shaft 156 is fixed an ordinary paper delivery fly 162 having a stop bar 157 near its lower end. Mounted on the rock shaft 156 is a pulley 158, see Figs. 18 and 35 17, to which is fixed one end of the strap 159, the other end of the strap being connected with a spring 160 fastened to the main frame, see Fig. 1. Shaft 156 also carries a friction pulley 161 arranged to co-40 operate with the friction wheel 138, for which purpose the friction strip 139 on the wheel 138 is provided. When friction wheel 138 rotates, its friction surface drives pulley 161 during the time that the friction strip 45 is in contact with this pulley, thereby rocking the shaft 156 and causing the delivery fly 162 to move backward from its receiving position shown in Fig. 1 to deposit the paper tubes on a table that have been delivered to it by the tapes 141 and 142. When the friction strip 139 has passed out 50 of contact with the pulley 161, the strap 159 rocks the shaft 136 backward to return the delivery fly to its receiving position.

55 When the front or seamed edge of the paper tube has been caught between the tapes 141 and 142 upon the forward movement of the pan 129, the tube is carried by these tapes over the roll 143 from which 60 it is deposited upon the delivery fly 162, the stop bar 157 preventing the tube from sliding off the fly.

While the specific machine herein shown and described is primarily designed as a 65 whole to work on crinkled paper and to

form tubes thereof, various features and combinations thereof may be advantageously employed to work on plain paper and in the fabrication of various articles, as will be readily understood. The invention in its 70 broader aspect is not restricted, therefore, to mechanism for working on crinkled paper only or designed to fabricate only tubes. Furthermore, if desired, the paper may be fed to the machine in separate 75 sheets instead of from a roll in the form of a continuous web.

What I claim is:

1. In a machine of the character described, a support for the paper having a 80 crease-forming channel therein transverse to the direction of travel of the paper; a crease-forming knife coöperating with said channel; and flap-folding means carried by said support adapted to fold a flap of the 85 paper projecting from the channel at one side thereof down upon the paper projecting from the channel at the other side.

2. In a machine of the character described, a support for the paper having a 90 crease-forming channel therein transverse to the direction of travel of the paper; a crease-forming knife coöperating with said channel; flap-folding means carried by said support adapted to fold a flap of the paper 95 projecting from the channel at one side thereof down upon the paper projecting from the channel at the other side; and means for applying an adhesive substance to unite the flap to the body of the paper. 100

3. In a machine of the character described, a support for the paper having a crease-forming channel therein transverse to the direction of travel of the paper; a crease-forming knife coöperating with said 105 channel; and flap folding means adapted to fold a flap of the paper projecting from the channel at one side thereof down upon the paper projecting from the channel at the other side, said means comprising a bar 110 normally extending beneath the flap, and devices for actuating it.

4. In a machine of the character described, a support for the paper having a crease-forming channel therein transverse to the direction of travel of the paper; a crease-forming knife coöperating with said channel; flap-folding means carried by said support adapted to fold a flap of the paper 115 projecting from the channel at one side thereof down upon the paper projecting from the channel at the other side; and grippers to hold the crease in the channel during the operation of said flap-folding means. 120

5. In a machine of the character described, a supporting roll for the paper having a crease-forming channel therein transverse to the direction of travel of the paper; a crease-forming knife coöperating with 130

said channel; and flap-folding means carried by said roll adapted to fold a flap of the paper projecting from the channel at one side thereof down upon the paper projecting from the channel at the other side.

5 6. In a machine of the character described, a supporting roll for the paper having a crease-forming channel therein transverse to the direction of travel of the paper; a crease-forming knife coöperating with said channel; flap-folding means adapted to fold a flap of the paper projecting from the channel at one side thereof down upon the paper projecting from the channel at the other side; and means for applying an adhesive substance to unite the flap to the body of the paper.

10 7. In a machine of the character described, a supporting roll for the paper having a crease-forming channel therein transverse to the direction of travel of the paper; a crease-forming knife coöperating with said channel; and flap-folding means adapted to fold a flap of the paper projecting from the channel at the other side, said means comprising a bar normally extending beneath the flap, and devices for actuating it.

15 8. In a machine of the character described, a supporting roll for the paper having a crease-forming channel therein transverse to the direction of travel of the paper; a crease-forming knife coöperating with said channel; flap-folding means carried by said roll adapted to fold a flap of the paper projecting from the channel at one side thereof down upon the paper projecting from the channel at the other side; and grippers to hold the crease in the channel during the operation of said flap-folding means.

20 9. In a machine of the character described, a support for the paper having a crease-forming channel therein transverse to the direction of travel of the paper; a crease-forming knife coöperating with said channel; flap-folding means adapted to fold a flap of the paper projecting from the channel at one side thereof down upon the paper projecting from the channel at the other side, said means comprising a bar normally extending beneath the flap, and devices for actuating it; and means for applying an adhesive substance to unite the flap to the body of the paper.

25 10. In a machine of the character described, a support for the paper having a crease-forming channel therein transverse to the direction of travel of the paper; a crease-forming knife coöperating with said channel; flap-folding means adapted to fold a flap of the paper projecting from the channel at one side thereof down upon the paper projecting from the channel at the other side, said means comprising a bar normally extending beneath the flap, and devices for

actuating it; and grippers to hold the crease in the channel during the operation of said flap-folding means.

11. In a machine of the character described, a support for the paper having a crease-forming channel therein transverse to the direction of travel of the paper; a crease-forming knife coöperating with said channel; flap-folding means adapted to fold a flap of the paper projecting from the channel at one side thereof down upon the paper projecting from the channel at the other side, said means comprising a bar normally extending beneath the flap, and devices for actuating it; means for applying an adhesive substance to unite the flap to the body of the paper; and grippers to hold the crease in the channel during the operation of said flap-folding means.

12. In a machine of the character described, a supporting roll for the paper having a crease-forming channel therein transverse to the direction of travel of the paper; a crease-forming knife coöperating with said channel; flap-folding means adapted to fold a flap of the paper projecting from the channel at one side thereof down upon the paper projecting from the channel at the other side, said means comprising a bar normally extending beneath the flap, and devices for actuating it; and grippers to hold the crease in the channel during the operation of said flap-folding means.

13. In a machine of the character described, a supporting roll for the paper having a crease-forming channel therein transverse to the direction of travel of the paper; a crease-forming knife coöperating with said channel; flap-folding means carried by said roll adapted to fold a flap of the paper projecting from the channel at one side thereof down upon the paper projecting from the channel at the other side; means for applying an adhesive substance to unite the flap to the body of the paper; and grippers to hold the crease in the channel during the operation of said flap-folding means.

14. In a machine of the character described, a supporting roll for the paper having a crease-forming channel therein transverse to the direction of travel of the paper; a crease-forming knife coöperating with said channel; and flap-folding means adapted to fold a flap of the paper projecting from the channel at one side thereof down upon the paper projecting from the channel at the other side, said means including a bar normally extending beneath the flap, arms carrying said bar and centered on the shaft of the roll and devices for actuating the arms and bar.

15. In a machine of the character described, a supporting roll for the paper having a crease-forming channel therein transverse to the direction of travel of the paper;

means for delivering to said roll a length of paper folded on itself on a line transverse to its direction of travel; a crease-forming knife coöperating with said channel; and flap-folding means adapted to fold a flap of the paper projecting from the channel at one side thereof down upon the paper projecting from the channel at the other side.

16. In a machine of the character described, a supporting roll for the paper having a crease-forming channel therein transverse to the direction of travel of the paper; means for severing a length of paper from a web and delivering it to said roll folded on itself on a line transverse to its direction of travel; a crease-forming knife coöperating with said channel; and flap-folding means adapted to fold a flap of the paper projecting from the channel at one side thereof down upon the paper projecting from the channel at the other side.

17. In a machine of the character described, a supporting roll for the paper having a crease-forming channel therein transverse to the direction of travel of the paper; means for severing a length of paper from a web and delivering it to said roll folded on itself on a line transverse to its direction of travel; a crease-forming knife coöperating with said channel; flap-folding means adapted to fold a flap of the paper projecting from the channel at one side thereof down upon the paper projecting from the channel at the other side; and grippers to hold the crease in the channel during the operation of said flap-folding means.

18. In a machine of the character described, a supporting roll for the paper having a crease-forming channel therein transverse to the direction of travel of the paper; means for severing a length of paper from a web and delivering it folded over on itself to said roll; a crease-forming knife coöperating with said channel; flap-folding means adapted to fold a flap of the paper projecting from the channel at one side thereof down upon the paper projecting from the channel at the other side, said means comprising a bar normally extending beneath the flap, and devices for actuating it; and grippers to hold the crease in the channel during the operation of said flap-folding means.

19. In a machine of the character described, a supporting roll for the paper having a crease-forming channel therein transverse to the direction of travel of the paper; means for delivering a folded length of paper to said roll; a crease-forming knife coöperating with said channel; and flap-folding means adapted to fold a flap of the paper projecting from the channel at one side thereof down upon the paper projecting from the channel at the other side, said means comprising a bar normally extending

beneath the flap, and devices for actuating it.

20. In a machine of the character described, a pair of coöperating rolls arranged to receive between them a web of paper; means associated with one of the rolls for engaging the web to conduct a predetermined length of it around on said roll; means associated with said rolls for severing said length of paper from the web; a support; and means to deliver the severed length of paper folded over on itself to the support.

21. In a machine of the character described, a pair of coöperating rolls arranged to receive between them a web of paper; means associated with one of the rolls for engaging the web to conduct a predetermined length of it around on said roll; means associated with said rolls for severing said length of paper from the web; a support; means to deliver the severed length of paper folded over on itself to the support; associated with said support for forming a seam at the adjoining margins of the folded paper.

22. In a machine of the character described, a pair of coöperating rolls arranged to receive between them a web of paper; means associated with one of the rolls for engaging the web to conduct a predetermined length of it around on said roll; means associated with said rolls for severing said length of paper from the web; a third roll; and means to deliver the severed length of paper folded over on itself to the third roll.

23. In a machine of the character described, a pair of coöperating rolls arranged to receive between them a web of paper; means associated with one of the rolls for engaging the web to conduct a predetermined length of it around on said roll; means associated with said rolls for severing said length of paper from the web; a third roll; means to deliver the severed length of paper folded over on itself to the third roll; and means associated with said third roll for forming a seam at the adjoining margins of the folded paper.

24. In a machine of the character described, a pair of coöperating rolls arranged to receive between them a web of paper; means associated with one of the rolls for engaging the web to conduct a predetermined length of it around on said roll; means associated with said rolls for severing said length of paper from the web; a third roll; grippers on said third roll adapted to engage the paper in a fold along a medial line thereof and conduct the paper in a fold on itself around on said third roll; and means associated with said third roll for forming a seam at the rear margins of the folded paper.

25. In a machine of the character described, a pair of coöperating rolls arranged

- to receive between them a web of paper; means associated with one of the rolls for engaging the web to conduct a predetermined length of it around on said roll; 5 means associated with said rolls for severing said length of paper from the web; a support; means to deliver the severed length of paper folded over on itself to the support; and means associated with said support; 10 port for forming a seam at the adjoining margins of the folded paper, said means including a crease-forming channel in said support, a crease-forming knife coöperating with said channel and a flap-folding device.
- 15 26. In a machine of the character described, a pair of coöperating rolls arranged to receive between them a web of paper; means associated with one of the rolls for engaging the web to conduct a predetermined length of it around on said roll; 20 means associated with said rolls for severing said length of paper from the web; a third roll; means to deliver the severed length of paper folding over on itself to the third roll; and means associated with said third roll for forming a seam at the adjoining margins of the folded paper, said means including a crease-forming channel in said third roll, a crease-forming knife coöperating with said channel and a flap-folding device.
- 25 27. In a machine of the character described, a pair of coöperating rolls arranged to receive between them a web of paper; 30 means associated with one of the rolls for engaging the web to conduct a predetermined length of it around on said roll; means associated with said rolls for severing said length of paper from the web; a third roll, grippers on said third roll adapted to engage the paper in a fold along a medial line thereof and conduct the paper in a fold on itself around on said third roll; and means associated with said third roll for 35 forming a seam at the rear margins of the folded paper, said means including a crease-forming channel in said third roll, a crease-forming knife coöperating with said channel and a flap-folding device.
- 40 28. In a machine of the character described, a pair of coöperating rolls arranged to receive between them a web of paper; means associated with one of the rolls for engaging the web to conduct a predetermined length of it around on said roll; a fold-forming knife on said roll; means associated with said rolls for severing said length of paper from the web; a third roll; grippers on said third roll adapted to engage the 45 paper in a crease at said fold-forming knife and conduct the paper in a fold on itself around on said third roll; and means associated with said third roll for forming a seam at the rear margins of the folded 50 paper.
- 55 29. In a machine of the character described, a supporting roll for the paper having a crease-forming channel therein transverse to the direction of travel of the paper; a second roll carrying a crease-forming 60 knife coöperating with said channel; flap-folding means carried by said roll adapted to fold a flap of the paper projecting from the channel at one side thereof down upon the paper projecting from the channel at the other side; and means carried by said second roll for applying an adhesive substance to said flap.
- 65 30. In a machine of the character described, a supporting roll for the paper having a crease-forming channel therein transverse to the direction of travel of the paper; 70 a second roll carrying a crease-forming knife coöperating with said channel; flap-folding means adapted to fold a flap of the paper projecting from the channel at one side thereof down upon the paper projecting from the channel at the other side, said means comprising a bar normally extending beneath the flap, and devices for actuating it; grippers to hold the crease in the channel during the operation of said flap-folding means; and means carried by said second roll for applying an adhesive substance to 75 said flap.
- 80 31. In a machine of the character described, a pair of coöperating rolls arranged to receive between them a web of paper; means carried by one of the rolls for engaging the web to conduct a predetermined 85 length of it around on said roll; means associated with said rolls for severing said length of paper from the web; a third roll; grippers on said third roll adapted to engage the paper in a fold along a medial line 90 thereof and conduct the paper in a fold on itself around on said third roll, said third roll being provided with a crease-forming channel; flap-folding means carried with said third roll and adapted to fold a flap of the paper projecting from said channel at one side thereof down upon the paper projecting from the channel at the other side; and a fourth roll carrying a crease-forming 95 knife coöperating with said channel and also carrying means for applying an adhesive substance to said flap.
- 100 32. In a machine of the character described, a pair of coöperating rolls arranged to receive between them a web of paper; means carried by one of the rolls for engaging the web to conduct a predetermined length of it around on said roll; means associated with said rolls for severing said length of paper from the web; a third roll, grippers on said third roll adapted to engage the paper in a fold along a medial line 105 thereof and conduct the paper in a fold on itself around on said third roll, said third roll being provided with a crease-forming 110 knife coöperating with said channel and also carrying means for applying an adhesive substance to said flap.
- 115 33. In a machine of the character described, a pair of coöperating rolls arranged to receive between them a web of paper; means carried by one of the rolls for engaging the web to conduct a predetermined length of it around on said roll; means associated with said rolls for severing said length of paper from the web; a third roll, grippers on said third roll adapted to engage the paper in a fold along a medial line 120 thereof and conduct the paper in a fold on itself around on said third roll, said third roll being provided with a crease-forming 125 knife coöperating with said channel and also carrying means for applying an adhesive substance to said flap.
- 130

channel; flap-folding means carried with said third roll and adapted to fold a flap of the paper projecting from said channel at one side thereof down upon the paper projecting from the channel at the other side, said means including a bar normally extending beneath the flap, arms carrying said bar and centered on the shaft of the roll and devices for actuating the arms and bar; 5 grippers carried by said third roll to hold the crease in said channel during the operation of said flap-folding means; and a fourth roll carrying a crease-forming knife coöperating with said channel and also carrying means for applying an adhesive substance to said flap.

33. In a machine of the character described, a support for the paper having a crease-forming channel therein transverse 20 to the direction of travel of the paper; a crease-forming knife coöperating with said channel; flap-folding means adapted to fold a flap of the paper projecting from the channel at one side thereof down upon the paper 25 projecting from the channel at the other side, said means comprising a bar normally extending beneath the flap, and devices for actuating it; means for applying an adhesive substance to unite the flap to the body of the paper; and a pressure device adapted to contact with said bar to squeeze down the folded over flap.

34. In a machine of the character described, a supporting roll for the paper 35 having a crease-forming channel therein transverse to the direction of travel of the paper; a crease-forming knife coöperating with said channel; and flap-folding means adapted to fold a flap of the paper projecting from the channel at one side thereof down upon the paper projecting from the channel at the other side, said means including a bar normally extending beneath the flap, arms carrying said bar and centered about the shaft of the roll, fixed cams to elevate the bar and move it forward and springs to return it to normal position.

35. In a machine of the character described, a supporting roll for the paper 50 having a crease-forming channel therein transverse to the direction of travel of the paper; a crease-forming knife coöperating with said channel; flap-folding means adapted to fold a flap of the paper projecting from the channel at one side thereof down upon the paper projecting from the channel at the other side, said means including a bar normally extending beneath the flap, arms carrying said bar and centered about the shaft of the roll, fixed cams to elevate the bar and move it forward and springs to return it to normal position; and a pressure device adapted to contact with said bar to squeeze down the folded over 65 flap.

36. In a machine of the character described, a traveling support; means for depositing thereon a sheet of paper folded on itself on a line transverse to its direction of travel; and seam-forming means operating 70 on the transverse margins of the folded sheet to form a tube.

37. In a machine of the character described, a roll adapted to carry a sheet of paper thereon; a traveling support to receive the paper from said roll; grippers on said support adapted to engage the sheet along a medial line thereof and conduct it in a fold on itself along on said support; and means associated with said support for 80 forming a seam at the adjoining margins of the folded sheet.

38. In a machine of the character described, a roll adapted to carry a sheet of paper thereon; a traveling support to receive the paper from said roll; grippers on said support adapted to engage the sheet along a medial line thereof and conduct it in a fold on itself along on said support; and means associated with said support for 85 forming a seam at the adjoining margins of the folded sheet, said means including a crease-forming channel in said support, a crease-forming knife coöperating with said channel and flap-folding means.

39. In a machine of the character described, a traveling support; means for depositing thereon a sheet of paper folded on itself on a line transverse to its direction of travel; and seam-forming means associated 100 with said support and operating on the transverse margins of the folded sheet to form a tube.

40. In a machine of the character described, a roll adapted to carry a sheet of paper thereon; a second roll to receive the paper from said first mentioned roll; grippers on said second roll adapted to engage the sheet along a medial line thereof and conduct it in a fold on itself around on said 105 second roll; and means associated with said second roll for forming a seam at the adjoining margins of the folded sheet.

41. In a machine of the character described, a roll adapted to carry a sheet of paper thereon; a second roll to receive the paper from said first mentioned roll; grippers on said second roll adapted to engage the sheet along a medial line thereof and conduct it in a fold on itself around on said 115 second roll; and means associated with said second roll for forming a seam at the adjoining margins of the folded sheet, said means including a crease-forming channel in said second roll, a crease-forming knife 120 coöperating with said channel and flap-forming means.

42. In a machine of the character described, a roll; means for depositing thereon a sheet of paper folded on itself on a line 130

transverse to its direction of travel; and seam-forming means associated with said support and operating on the transverse margins of the folded sheet to form a tube.

5 43. In a machine of the character described, a traveling support adapted to carry a sheet of paper thereon; a roll to receive the paper from said traveling support; grippers on said roll adapted to engage the 10 sheet along a medial line thereof and conduct it in a fold on itself around on said roll; and means associated with said roll for forming a seam at the adjoining margins of the folded sheet.

15 44. In a machine of the character described, the combination of a traveling support adapted to carry thereon a sheet of paper folded on itself on a line transverse to the direction of travel of the paper; and 20 seam-forming means associated with said support adapted to form a seam at the adjoining margins of the folded sheet transverse to the direction of travel of the paper.

25 45. In a machine of the character described, the combination of a supporting roll adapted to carry thereon a sheet of paper folded on itself on a line transverse to the direction of travel of the paper; and seam-forming means associated with said 30 roll adapted to form a seam at the adjoining margins of the folded sheet transverse to the direction of travel of the paper.

40 46. In a machine of the character described, the combination of a traveling support adapted to carry thereon a sheet of paper folded on itself on a line transverse to the direction of travel of the paper; and seam-forming means associated with said support adapted to form a seam at the adjoining 45 margins of the folded sheet transverse to the direction of travel of the paper, said seam-forming means including a crease-forming channel in said support, a crease-forming knife coöperating with said channel and flap-folding means.

50 47. In a machine of the character described, the combination of a supporting roll adapted to carry thereon a sheet of paper folded on itself on a line transverse to the direction of travel of the paper; and seam-forming means associated with said roll adapted to form a seam at the adjoining margins of the folded sheet transverse to the direction of travel of the paper, said 55 seam-forming means including a crease-forming channel in said roll, a crease-forming knife coöperating with said channel and flap-folding means.

60 48. In a machine of the character described, the combination of a supporting roll adapted to carry thereon a sheet of paper folded on itself on a line transverse to the direction of travel of the paper; and seam-forming means associated with said 65 roll adjusted to form a seam at the adjoining

70 margins of the folded sheet transverse to the direction of travel of the paper, said seam-forming means including a crease-forming channel in said roll, a crease-forming knife coöperating with said channel and flap-folding means including a bar normally extending beneath a flap formed in the paper adjoining said crease-forming channel, arms carrying said bar and centered on the shaft of the roll and devices for actuating 75 the arms and bar.

49. In a paper folding mechanism, the combination of a support for the paper having a channel therein adapted to contain a crease or fold of the paper; grippers 80 to hold the crease in said channel; a bar extending across the support at one side of said channel; and means to carry the bar to the opposite side of the channel and back to its initial position. 85

50. In a paper folding mechanism, the combination of a support for the paper having a channel therein adapted to contain a crease or fold of the paper; grippers to hold the crease in said channel; a bar extending 90 across the support at one side of said channel; and means to carry the bar to the opposite side of the channel and back to its initial position, said means including pivoted arms carrying the bar, cams to elevate 95 the bar and move it forward and springs to return it to initial position.

51. In a paper folding mechanism, the combination of a roll to carry the paper and having a channel in its periphery parallel 100 with the axis of the roll; grippers to hold a crease or fold in a sheet of paper in said channel; a bar extending across the roll at one side of said channel; and means to carry the bar to the opposite side of the channel 105 and back to its initial position.

52. In a paper folding mechanism, the combination of a roll to carry the paper and having a channel in its periphery parallel with the axis of the roll; grippers to 110 hold a crease or fold in a sheet of paper in said channel; a bar extending across the roll at one side of said channel; and means to carry the bar to the opposite side of the channel and back to its initial position, said 115 means including pivoted arms carrying said bar and centered about the shaft of said roll, and cams and springs to actuate said arms and suitably arranged to move the bar from one side of the channel to the 120 other side thereof and back again.

53. A tube making machine comprising means for folding a blank along a line transverse to the direction of movement thereof and means for seaming the blank at its transverse margins. 125

54. A tube making machine comprising means for folding a blank along a line transverse to the direction of movement thereof and means for seaming the blank at its trans- 130

verse margins and applying an adhesive to one of said margins.

55. A tube making machine comprising means for cutting a blank, means for folding the blank along a line transverse to the direction of movement thereof and means for seaming the blank at its transverse margins.

56. A tube making machine comprising means for cutting a blank, means for folding the blank along a line transverse to the direction of movement thereof, and means for seaming the blank at its transverse margins and applying an adhesive to one of said margins.

57. A tube making machine comprising means for severing a web to form a blank, means for folding the blank along a line transverse to the direction of movement thereof and means for seaming the blank at its transverse margins.

58. A tube making machine comprising means for severing a web to form a blank, means for folding the blank along a line transverse to the direction of movement thereof and means for seaming the blank at its transverse margins and applying an adhesive to one of said margins.

59. A tube making machine comprising means for severing a web to form a blank, means for folding the blank along an off-center line transverse to the direction of movement thereof whereby the margins are disaligned, and means for seaming and flap-folding the blank at its transverse disaligned margins.

60. A tube making machine comprising means for severing a web to form a blank, means for folding the blank along an off-center line transverse to the direction of movement thereof whereby the margins are disaligned, and means for seaming, flap-folding and pasting the blank at its transverse disaligned margins.

61. In a tube making machine; a continuously moving mechanism which comprises means for folding a blank along a line transverse to the direction of movement thereof and means for seaming the blank at its transverse margins.

62. In a tube making machine, a continuously moving mechanism which comprises means for folding a blank along a line transverse to the direction of movement thereof and means for seaming the blank at its transverse margins and applying an adhesive to one of said margins.

63. In a tube making machine, a continuously moving mechanism which comprises means for cutting a blank, means for folding the blank along a line transverse to the direction of movement thereof and means for seaming the blank at its transverse margins.

64. In a tube making machine, a continu-

ously moving mechanism which comprises means for cutting a blank, means for folding the blank along a line transverse to the direction of movement thereof, and means for seaming the blank at its transverse margins and applying an adhesive to one of said margins.

65. In a tube making machine, a continuously moving mechanism which comprises means for severing a web to form a blank, means for folding the blank along a line transverse to the direction of movement thereof and means for seaming the blank at its transverse margins.

66. In a tube making machine, a continuously moving mechanism which comprises means for severing a web to form a blank, means for folding the blank along a line transverse to the direction of movement thereof and means for seaming the blank at its transverse margins and applying an adhesive to one of said margins.

67. In a tube making machine, a continuously moving mechanism which comprises means for severing a web to form a blank, means for folding the blank along an off-center line transverse to the direction of movement thereof whereby the margins are disaligned, and means for seaming and flap-folding the blank at its transverse disaligned margins.

68. In a tube making machine, a continuously moving mechanism which comprises means for severing a web to form a blank, means for folding the blank along an off-center line transverse to the direction of movement thereof whereby the margins are disaligned, and means for seaming, flap-folding and pasting the blank at its transverse disaligned margins.

69. In a machine of the character described, a roll having disposed about the periphery thereof gripping means for folding a blank of paper and means for transversely creasing the blank remotely from the fold.

70. In a machine of the character described, a roll having disposed about the periphery thereof gripping means for folding a blank of paper and means for transversely creasing the blank remotely from the fold and means for flap-folding the blank.

71. The method of making a tube which comprises first severing a web to form a blank, then folding the blank doubled upon itself on a transverse line intermediate the severed ends, and then seaming the transverse margins.

72. The method of making a tube which comprises first severing a web to form a blank, then folding the blank doubled upon itself on a transverse line intermediate the severed ends, and then seaming and pasting the transverse margins.

73. The method of making tubes from a web of paper which comprises first severing the web transversely to form a blank, then transversely folding the blank non-centrally whereby the ends or margins are disaligned, then severing the blank non-centrally whereby the ends or margins are disaligned, and then seaming and pasting the transverse margins.

74. The method of making tubes from a web of paper which comprises first severing

the web transversely to form a blank, then transversely folding the blank non-centrally whereby the ends or margins are disaligned, then seaming the transverse margins and then pasting and flap-folding the longer transverse margins.

This specification signed this 10th day of May, A. D. 1917.

HOWARD G. WIDMER.
